DESIGN FOR A RANGE

John D. Coleman, Detroit, Mich., assignor to The
Aviation Corporation, New York, N. Y., a cor-
poration of Delaware

Application June 4, 1945, Serial No. 119,885

Term of patent 14 years

(Cl. D81—4)

To all whom it may concern:

Be it known that I, John D. Coleman, a citizen
of the United States, residing at Detroit, in the
county of Wayne and State of Michigan, have
invented a new, original, and ornamental Design
for a Range, of which the following is a speci-
fication, reference being had to the accompany-
ing drawings, forming a part thereof.

In the drawings:

Fig. 1 is a perspective of a range showing
my new design; and

Fig. 2 is an elevation of one side thereof. The
other side is substantially like that shown.

I claim:

The ornamental design for a range, substan-
tially as shown and described.

JOHN D. COLEMAN.
